UNITED STATES PATENT OFFICE.

DAVID S. HEEBNER, ISAAC D. HEEBNER, AND WILLIAM D. HEEBNER, OF LANSDALE, PENNSYLVANIA.

BRAKE FOR MACHINE-WAGONS.

SPECIFICATION forming part of Letters Patent No. 286,300, dated October 9, 1838.

Application filed August 10, 1833. (No model.)

To all whom it may concern:

Be it known that we, DAVID S. HEEBNER, ISAAC D. HEEBNER, and WILLIAM D. HEEBNER, of Lansdale, in the county of Montgomery and State of Pennsylvania, have invented a certain new and useful Brake for Machine-Wagons, to be used as an attachment for thrashing-machines, portable engines, &c.; and we do hereby declare the following to be a full, clear, and exact description of the same, reference being had to the accompanying drawings, forming part of this specification, and to the figures and letters of reference marked thereon.

15 Our invention has for its object to provide improved means for locking stationary, while in operation, the transporting-wheels of thrashing-machines, horse-powers, baling-presses, portable engines, and other portable machines; 20 and it consists in certain novel devices and combinations of parts, which we will first describe, and then point out particularly in the claims at the end of this specification.

In the accompanying drawings, to which reference is made, Figure 1 represents a side elevation of a thrashing-machine having our improvement applied thereto. Fig. 2 is a bottom plan view of the same. Fig. 3 is a sectional view taken on the line *x x* of Fig. 1. 30 Fig. 4 is a sectional view taken on the line *y y* of Fig. 3. Fig. 5 is a detail view, showing, particularly, the inclined bearing-faces of the brake-shoe.

Similar letters in the several figures indicate 35 like parts.

We have shown our invention as applied to a thrashing-machine, and will describe it so applied; but it is evident that application of it could be made to various other machines 40 with the same effect.

A represents the thrashing-machine, mounted on transporting-wheels B and C at front and rear, respectively, as shown.

Across the frame of the machine, and under 45 the bottom timbers or sills thereof, we extend brake-beams D E, and provide such beams at opposite sides with brake-shoes F, as shown, the shoes of the brake-beam D being adapted to co-operate with the front wheels, and the shoes

of the brake-beam E being adapted to co-operate with the hind wheels.

Diagonally through the beams D E we pass the shanks of what we term "clamping-bolts" G G'. Each of these bolts at its upper end is bent or formed with an angular projection, *g*, 55 which is adapted to engage with one or another of a series of notches, *i*, in a plate, I, secured upon the lower timber of the thrasher, as shown, while the lower end of said bolt passes first through a thimble or boss on the 60 opposite side of the beam, where it is screw-threaded, and is provided with a clamping-nut, J. From this construction it will be seen that when it is desired to lock the wheels tightly, so as to steady the machine and prevent 65 the vibration and loosening of its parts, the angular ends of the clamping-bolts are engaged with one or the other of the series of notches in the notched plates, and the clamping-nuts are screwed tightly up until the shoes 70 on the brake-beams are made to bear tightly upon the rims of the wheels. The brake-beams are so situated under the machine that a tightening of the bolts causes them to brace and support the middle portions of the machine, while the crowding of the brake-shoes up onto the wheels causes the rims of the latter to support directly a great proportion of 75 the weight of the machine, and thus, in a measure, relieve the axles. To further assist in 80 steadying the machine and holding the wheels tightly in position, we preferably incline the bearing-faces of the brake-shoes inwardly, so that when clamped to the wheels their outer portions will engage with the tire, and as the 85 pressure is increased will tend to crowd the wheels inward upon their spindles and against the shoulders of the axles. In this way all rotation of the wheel, as well as any lateral sliding or rocking action of them, is prevented, 90 and the whole support of the machine is thus bound and tied immovably together. To relieve the wheels from the brake-shoes it is only necessary to loosen the clamping-nuts, and then rotate the clamping-bolts until their angular ends are disengaged from the notches in 95 the plates and project outward, as shown by the dotted lines in Fig. 3, when the whole

brake-beam and its connected parts can be removed.

The devices for locking the front and hind wheels are constructed substantially the same; 5 but the latter may be, if desired, arranged as the permanent brake contrivance of the machine, to be used, when desired, in transportation from place to place, by simply providing suitable guiding loops or straps, K K, for the 10 beam to work in, and in applying to the beam any of the ordinary lock-lever devices in common use. Of course, when so used the clamping-bolts and nuts will have to be so adjusted as to permit a limited sliding movement of the 15 beam in its guides.

Having thus described our invention, what we claim as new is—

1. As a means for locking the transporting-wheels of thrashing-machines and other portable machines and engines, a locking contrivance consisting of beams extending across and under the lower timbers or sills of the machine, having brake-shoes for co-operating with the wheels, in combination with bolts extending 20 diagonally from the beams to the frame of the machine, with means applied to said bolts for forcing the beams up against the timbers or sills of the machine, and their shoes upon the periphery of the wheels, so as to strengthen 25 and support the frame of the machine and transfer a proportion of the weight to the rims of the wheels, substantially as described.

2. The combination, with the machine or engine and its transporting-wheels, of the 30 brake-beams and their shoes, the clamping-bolts passed diagonally through the beams and

connected at one end to the frame of the machine or engine, and provided at the opposite end with nuts for clamping the beams up against the frame, and the shoes onto the wheel-rims, substantially as described. 40

3. The combination, with the machine or engine and its transporting-wheels, of the brake-beams and their shoes, the clamping-bolts extending diagonally from the beams 45 and having the angular end, the notched plates on the frame, and the clamping-nuts, the whole arranged and operating substantially as described.

4. The combination, with the machine or engine and its transporting-wheels, of the brake-beams and their shoes, the notched plates on the frame, and the clamping-bolts and nuts, said bolts having the angular heads and being capable of rotation, so as to be disengaged 50 from the notched plates, substantially as described.

5. The combination, with the machine and its supporting-wheels, of the rear brake-beam and its shoes, the diagonal clamping-rods and their nuts, the notched plates on the frame, and the guides for the brake-beam, whereby the latter is adapted to serve as an ordinary adjustable brake for use while transporting the machine, substantially as described. 60
